James Paterson, of Elizabeth, N.J.
asso. to

Deborah Powers, Albert E. Powers, and
Nathaniel B. Powers, of Lansburgh N.Y.
Letters Patent No. 1739, dated Feb. 17, 1862.

The schedule referred to in these Letters Patent and making part of the same.

To all whom it may concern:

Be it known that I, James Paterson, of the city of Elizabeth, in the County of Union, and State of New Jersey, have invented or produced a new and original design, for Floor Oil Cloths or other fabrics; and I do hereby declare that the following is a full, and exact description of the same viz: The pattern consists of two square tiles placed diamond-wise of the fabric, one being of light color with two ornamental lines of white near its margin, and an ornament in colors near its centre: the other of darker color with a line of black or marrone near its edge and a diamond of black or marrone in its centre upon which are placed ornaments in colors.

And what is claimed as my invention and desired to be secured by Letters Patent is the above described pattern as shown by the drawings accompanying this specification which is hereby declared to be a part of the same.
